1,000,000,

Serial No. 1,000,000. Letters Patent. Patented June 21, 1914.

Application filed February 19, 1913. Serial No. 4,787,487. Renewed June 21, 1914. Serial No. 773,848.

To all whom it may concern:

Be it known that L. BEAR, F. VERNON, a citizen of the United States, residing at Elmhurst, in the county of Cook and state of Illinois, have invented a new and useful improvement in Bed-Motors for Printing-PresSES, of which the following is a specification.

This invention relates to improvements in bed motions in machines of the character of printing presses.

The object of the invention is to provide a bed motion, or a bed, of the type indicated, such, for instance, as are commonly known as printing presses of the Madsen type, having a high speed of reciprocation, and one whereby, irrespective of the speed of the machine, the motion of the bed will be uniform.

Another object of the invention is to construct the reversing mechanism so that during the reversals, the forces across the reciprocating bed and tending to stop and start the same in the opposite direction will be exerted in a downward direction on the bed and parallel thereto, and thereby to keep it at all times in close relation with the bed supports, and prevent any tendency to throw the bed upwardly away from the supports during the reversing operation, which tendency is found in many of the forms of bed motions now commonly used in printing presses.

Another object of my invention is to so arrange the rocker, piston and reversing mechanism beneath the reciprocating bed, that a better support may be given beneath the same directly under the impression cylinder, and thus secure a more perfect impression.

My invention further consists in the novel construction of parts and devices and in the novel combinations of parts and devices herein shown, described or claimed.

In the drawings forming a part of the specification, Figure 1 is a longitudinal vertical section of a printing press showing my improvements applied thereto, and taken on the line 1-1 of Fig. 3. Fig. 2 is a similar longitudinal, vertical sectional view, taken on the line 2-2 of Fig. 3. Fig. 3 is a plan

view of the structure shown in Figs. 1 and 2, the bed being shown in dotted lines. Fig. 4 is a transverse, vertical section taken on the line 4-4 of Fig. 1. Fig. 5 is a view, similar to Fig. 4, taken on the line 5-5 of Fig. 1. Fig. 6 is a detail, sectional view of part of the reversing mechanism. Fig. 7 is a detail, sectional view of one of the reversing stops, taken on the line 7-7 of Fig. 1, and Fig. 8 is a diagrammatic view showing the movements of the wrist pin.

In the drawings, 10 denotes any suitable base adapted to support the various parts of the mechanism, 11 being provided with a plurality of vertical uprights or standards 11 which are adapted to support the ways 12 in which reciprocates the bed 13, laterally extending from the ways 12 and a pair of spaced standards 14, in which is rotatably mounted a shaft 15 adapted to support and rotate the impression cylinder 16. The impression cylinder 16 is provided with a base 17 supported by means of a gear 18 secured to shaft 15, the said base 17 being provided with a pair of interlocking gears, the said base 17 carrying a gear 19 secured to the shaft 15, and 18 being interlocked, respectively, with a gear 20 secured to a shaft 21, the latter being driven by means of a belt 22, the said belt 22 being supported by a pair of spaced, laterally spaced standards 23, the latter being laterally above the latter for reasons hereininafter described, and the base 17 being secured to the shaft 15, as shown in Fig. 1, opposite the impression cylinder 16, the base 17 being secured to the standards 14, and the standards 14 being secured to the base 10.

The base 17 is provided with a piston 23, which is secured to the shaft 21, the latter being driven by means of a belt 22, the said belt 22 being supported by a pair of spaced standards 23, the latter being secured to the base 10, as shown in Fig. 1, opposite the impression cylinder 16, the base 17 being secured to the standards 14, and the standards 14 being secured to the base 10. The piston 23 is secured laterally on its shaft 21, which has a stationary axis and a gear 24 secured to its shaft 21, a flange 25 being in a groove 26 in the double gear 27, whereby, when the latter is reciprocated, the gear or pinion 28 is also reciprocated, thus being adapted to be driven into and out of gear with the rock-

24. The double gear 27 is reciprocated by means of a lever 32, pivoted to a lug 33 of the frame, the upper end of the lever 32 engaging in a groove 34 of the collar 67, and the lower end of said lever 32 being provided with a roller 35, preferably provided with an anti-friction roller, and running in a cam groove 36 on the cam 37, the same being mounted on a stub shaft 38 mounted in the frame, said shaft 38 being rotated from the power shaft 18 by means of intermediate gearing, comprising a gear 39, keyed to the shaft 21 and gear 49 keyed to the shaft 38. The double gear 27 has one portion thereof adapted to engage with the rack 25 and move the bed 13 in the opposite direction to that caused by the pinion or gear 26. The gears 26, 27 are so arranged that they alternately engage the racks 24 and 25, thus moving the bed in opposite directions. The rack 24 being higher than the rack 25, the double gear 27 will clear the same in all positions.

Secured to the underside of the bed 13, near each end thereof, are reversing shoes 41 and 42. The shoe 41 is provided with a vertically extending lug 43 and a securing member 44, the latter being disposed substantially at forty-five degrees to the bed. The reversing shoe 41 is furthermore provided with a portion having an active face 45, the same being disposed at forty-five degrees to the plane of the bed, and by the term "active face" is meant that portion of the shoe which, while in engagement with the rotating wrist pin or crank pin herein-after described, is utilized to stop and start the bed, in contradistinction to faces or slots in shoes used in some forms of printing presses which are adapted merely to allow the entrance of the wrist or crank pin before the latter begins to act to stop and start the bed. Mounted on the shoe 41 is a pivoted gate 46, the same being located opposite the active face 45 of the shoe, and being normally held retracted in the offset portion 47 of the shoe by means of a spring 48. The reversing shoe 42 is constructed similarly to the shoe 41 and is provided with an active face 68, the same being disposed at forty-five degrees to the plane of the bed, the faces 45 and 68 being oppositely arranged, as shown in Fig. 1. The shoe 42 is furthermore provided with a pivoted gate 49, mounted similarly to the gate 46 and also spring controlled. Mounted on the shaft 21 at the inner end thereof is a disk 51, provided with a crank or wrist pin provided with an anti-friction roller 52, adapted to engage with the face 68 of the shoe 42. Mounted on a shaft 53 located to the right of the shaft 21, as seen in Fig. 1, is a second member 54 also provided with a wrist or crank pin 55, having an anti-friction roller 56 at the end thereof, the same being adapt- ed to engage with the face 45 of the shoe 41. The shaft 53 and member 54 thereon are rotated by means of a gear 57 keyed thereto at its outer end, the gear 57 meshing with a gear 58 on the cross shaft 21, whereby it will be evident that the wrist pins 51 and 55 are oppositely rotated. Each of the gates 46 and 49 is adapted to be thrown inwardly at about the time the corresponding wrist pin is engaged with the active face on the reversing shoe, by means of a rod 59 secured to the gate, each of said rods 59 being provided with a roller at its outer end and adapted to be engaged by a cam 60, secured to the side of the machine. As clearly shown in Fig. 1, each of the plain active faces 45 and 68 has portions extending both above and below a horizontal plane passing through the respective axes of the shafts 52 and 21 which form the centers of rotation of the wrist pins engaging respectively the faces 45 and 68.

The operation of the bed motion is as follows: When the bed is in the position as shown in Fig. 1, the same is going toward the left, as viewed in said figure, and the wrist pin 51 is rotated in a counter-clockwise direction. As previously stated, the gate 49 on the shoe 42 will be depressed except when the roller on the pin 59 on the gate comes in contact with the cam 60 so that the pin 51 will clear the gate 49 and come in contact with the face 68 of the shoe 42. At this stage of the movement, the gate 49 is operated by a cam 60. As the bed continues its movement to the left, as viewed in Fig. 1, the same will be slowed down by means of the wrist or crank pin 51 engaging the face 68, it being obvious that the wrist pin 51 will exert a force having no upward component on the bed through the shoe during the slowing down or stopping of the latter. As the wrist pin 51 continues to rotate, the bed will be stopped when the pin 51 is in a line perpendicular to the face 68 and passing through the center of the shaft 21 about which the pin 51 rotates. As the pin 51 now continues to rotate, the same will move along the face 68 and start the bed in the opposite direction, or, in other words, to the right, as viewed in Fig. 1. During this starting movement, the pressure is exerted by the pin 51 with a downward component on the face 68, so that it will be apparent that at all times while the pin 51 is in engagement with the active face 68 of the shoe, the forces tending to stop and start the bed will pull the bed downward and thus prevent any tendency to throw the same upward. Upon the continued rotation of the pin 51, the same will leave the slot formed by the face 68 and the keeper 49 at the lower end thereof, at which time the gear 26 will be in engagement with the rack 24. As the bed 13

comes to the right to begin the second movement, the right of the gate 46, the gate 46 on the side 41 and will come in contact with the active face 16 of the gate 41, whereas, in the gate 30 will be thrown inwardly by the scroll 31 and, as long as it continues to rotate, the scroll will move on the face 46 to the right and then start it in the reverse direction to the scroll 31 and later to the action of the gate 30 as the scroll 32. During said rotation, providing operations, the gates 30 and 31 are moved to their proper positions by means of the scroll 32, so that when each pair receives information from its corresponding face of the scroll, each will be reached by either one of the gates 30 or 31.

It will be evident that the ⁶⁵ ⁶⁶ ⁶⁷ ⁶⁸ ⁶⁹ ⁷⁰ ⁷¹ ⁷² ⁷³ ⁷⁴ ⁷⁵ ⁷⁶ ⁷⁷ ⁷⁸ ⁷⁹ ⁸⁰ ⁸¹ ⁸² ⁸³ ⁸⁴ ⁸⁵ ⁸⁶ ⁸⁷ ⁸⁸ ⁸⁹ ⁹⁰ ⁹¹ ⁹² ⁹³ ⁹⁴ ⁹⁵ ⁹⁶ ⁹⁷ ⁹⁸ ⁹⁹ ¹⁰⁰ ¹⁰¹ ¹⁰² ¹⁰³ ¹⁰⁴ ¹⁰⁵ ¹⁰⁶ ¹⁰⁷ ¹⁰⁸ ¹⁰⁹ ¹¹⁰ ¹¹¹ ¹¹² ¹¹³ ¹¹⁴ ¹¹⁵ ¹¹⁶ ⁸⁸⁸⁸⁸⁸⁸¹⁸ ⁸⁸⁸⁸⁸⁸⁸¹⁹ ⁸⁸⁸⁸⁸⁸⁸

The reason that the distance between the reciprocating bed and the base of the machine can be lessened is due to the fact that by employing a reversing shoe bearing an active face of a radius of the bed, the radius of rotation of the wheel or crank pin used in stopping and starting the bed, is compared with the radius of wire pins used

Another important feature of my invention resides in the fact that the amount of relative movement between the outer pin and the drive face during the stepping of the bed when the greatest strain is placed upon the wrist pin, is very slight and in fact the two parts of the wrist pin and the drive face are practically locked. This will be seen by referring to the diagrammatic sketch which shows that the wrist pin during the 130

- stopping movement has a slight vertical up and down movement between the points *o* and *p*. On the other hand, during the starting of the bed, at which time the strains on the wrist or crank pin are comparatively slight, the pin has a greater vertical movement or travel on the active face of the reversing shoe, namely, from the point *h* to the point *n*.
- 10 I have described my improvements in detail as applied to a printing press of a well known form, but it is obvious that many changes, variations and modifications may be made in the construction and application 15 of the same without departing from the spirit of the invention, and that the form which I have shown and described is merely illustrative, and all such changes, variations and modifications are contemplated as fall 20 within the scope of the claims appended hereto.

I claim:—

1. In a machine of the character described, in combination, a reciprocating bed 25 and means for reciprocating said bed, including a reversing shoe secured to the bed and having its active face disposed throughout its length at an angle of less than ninety degrees to the bed, and a rotating member 30 provided with a wrist or crank pin which engages said face of the shoe during the reversing movement of the bed, said pin being in engagement with the face during the entire time that the bed is being stopped from 35 going in one direction and started in the opposite direction and until the normal speed of the bed is reached.
2. In a machine of the character described, in combination, a frame, a reciprocating bed mounted in ways in said frame, and mechanism for reciprocating said bed, including a reversing shoe secured to the bed and having a single plain active face disposed at an angle less than a right angle to 45 the bed, and a rotating member provided with a wrist or crank pin adapted to intermittently engage said face of the shoe and stop and start the bed while in engagement with said face, said face of the shoe having 50 portions thereof extending both above and below a horizontal plane passing through the center of rotation of the rotating member.
3. In a machine of the character described, in combination, a frame provided 55 with ways, a bed adapted to reciprocate in said ways, and mechanism for reciprocating said bed including a reversing shoe secured to the bed and having a single plain, active face disposed at forty-five degrees to the 60 bed, and a rotating member provided with a wrist or crank pin adapted to intermittently engage said face of the shoe and both entirely stop and start the bed while in engagement with said face.
- 65 4. In a machine of the character de-

scribed, in combination, a reciprocating bed and means for reciprocating said bed including a reversing shoe secured to the bed and having its active face disposed throughout its length at an angle of less than ninety degrees to the bed, and a rotating member provided with a wrist or crank pin adapted to intermittently engage the said face of the shoe and both stop the bed as it is going in one direction and start the bed in the opposite direction while in engagement with said face, said shoe being also provided with a movable gate located opposite the active face.

5. In a machine of the character described, in combination, a frame provided with ways, a bed adapted to reciprocate in said ways, and mechanism for reciprocating said bed including a reversing shoe secured to the bed and having a plain, active face disposed at forty-five degrees to the bed, and a rotating member provided with a wrist or crank pin adapted to intermittently engage said face of the shoe and stop and start the bed while in engagement with said face, said shoe being also provided with a pivoted gate located opposite the active face.

6. In a machine of the character described, in combination, a frame, a reciprocating bed thereon and mechanism for reciprocating said bed, said mechanism including a pair of spaced reversing shoes secured to the bed, each shoe having its active face disposed throughout its length at an angle of less than ninety degrees to the bed, said faces being oppositely arranged, and a pair of oppositely rotating members, each provided with a wrist or crank pin adapted to intermittently engage one of said faces and stop and start the bed while in engagement with the face.

7. In a machine of the character described, in combination, a frame, a reciprocating bed and mechanism for reciprocating said bed including a pair of spaced reversing shoes secured to the bed, each shoe having a plain active face disposed at an angle of less than ninety degrees to the bed, said faces being oppositely arranged, and a pair of oppositely rotating members each provided with a wrist or crank pin adapted to intermittently engage one of said faces and stop and start the bed while in engagement therewith.

8. In a machine of the character described, in combination, a frame, a reciprocating bed and mechanism for reciprocating said bed, including a pair of spaced, reversing shoes secured to the bed, each shoe having a plain active face disposed at an angle of less than ninety degrees to the bed, said faces being oppositely arranged, and a pair of oppositely rotating members each provided with a wrist or crank pin adapted to intermittently engage one of said faces.

and stop and save the bed while in engagement therewith, each of said shoes being furthermore provided with a pivoted gate located opposite the active face.

9. In a printing press, in combination, an impression member, a reciprocating bed and mechanism for reciprocating said bed comprising a pair of laterally spaced rocks on the under side of the bed, a pair of upper fully rotating gears adapted to mesh alternately with said rocks, a depending and reciprocating structure carried in the bed having its outer face disposed throughout its length at an angle of less than ninety degrees to the face of the bed, an impression member having a surface in contact with the outer face of the depending structure adapted to engage and form of the structure a surface with a raised portion of the surface acting on the outer face of the impression member with a force.

41. In a pair of shoes having a bed, a pair of
42. supports for the bed, a pair of shoes, each
43. mechanism for the supports, each mechanism
44. comprising a pair of oppositely mounted numbers
45. the under side of each number being
46. oppositely rotating, the supports being
47. oppositely tilted and rotated, the first degree of
48. reversing the supports, their upper
49. ends of the bed being having a face, the
50. face disposed at an angle of less than forty-five
51. degrees to the bed, said faces being positioned
52. oppositely to each other, and a pair of oppo-
53. sitely rotating numbers, each having
54. mounted thereon a wrist or crank pin
55. adapted to engage with one of the faces of
56. the shoes to start and start the bed.

12. In a printing press, in combination, an impression member, a reciprocating bed and mechanism for reciprocating said bed comprising a pair of laterally spaced racks on the under side of the bed, a pair of oppositely rotating gears adapted to mesh alternately with said racks, a pair of depending reversing shoes secured to the bed and each provided with an active face disposed at an angle of less than forty degrees to the bed throughout its length, said faces being oppo-

hereupon provided with a wrist or neck
pivoted gate to engage one of said faces and
keep and shut the hel white in engagement
therewith, each of said gates being further
provided with a pivoted gate opposite
the active face thereto.

15. In a printing press in combination an impression cylinder, a reciprocating bed and a cylinder for reciprocating said bed, comprising a pair of racks, gears adapted to mesh with said racks alternately, and a pair of opposing reversing shoes secured to the bed near the ends thereof, each shoe being provided with a plain active face disposed at an angle of forty-five degrees to the bed, so as to pass over printing numbers, each provided with a slot or crank pin adapted to receive the active face of the shoe, and stop the shoe from being idle in engagement therewith, the numbers the faces having on the bed an angle of forty-five degrees and tend to move the shoe in the direction of the cylinder.

3. A variety of pens, in combination, with a central, cyclone, and, a resting bed and tent, the former, resting with bed and means as shown, the latter, being a pair of curved racks arranged on the side of the bed, a pair of curved, cyclone, pens, means for restraining a solid pen, substantially laterally, of the bed, said pens, means as adapted to substantially arrest with straight sides, a pair of dispensing, dispensing tubes, secured to the bed, one at each end, thereby, each of said tubes being provided with a pliable, active dispensing end, thereabout its length, at an angle of about forty-five degrees to the bed, the dispensing end being substantially horizontal, and

the following, consisting of four, each
with a white twist or cord, the wrapped
around the faces of the shoes to
keep them white in engagement
and to prevent them from being
soiled.

16. In a machine of the character described in condition 1, a compensating rod and mechanism for reciprocating and

- plain active face disposed at an angle of less than ninety degrees to the bed, a rotatable member provided with means adapted to engage the active face of the shoe intermittently and traverse said face and stop and start the bed while in contact therewith, said face of the shoe having portions thereof extending both above and below a horizontal plane passing through the center of rotation of the rotating member. 10
17. In a machine of the character described, in combination, a reciprocating bed and mechanism for reciprocating said bed, including a rack on the bed, a gear adapted to be engaged with and disengaged from said rack, a rotatable member provided with a wrist or crank pin thereon, a reversing shoe secured to said bed, said shoe having a single plain active face disposed at an angle of less than ninety degrees to the bed and with which said pin is adapted to engage to stop and start the bed, said active face of the shoe having portions thereof extending both above and below a horizontal plane passing through the center of rotation of the rotating member, said pin being rotatable about the same axis as said gear, and having a radius of rotation less than the radius of the pitch circle of the gear, whereby a multiplying effect in the movements of the bed is effected between the pin and the active face during the stepping and starting, substantially as specified. 20
18. In a printing press, in combination, a frame provided with ways, a bed mounted in said ways, an impression cylinder and mechanism for reciprocating said bed, said mechanism including a depending reversing shoe secured to the bed, and having a single active face thereon disposed at an angle throughout its length of less than ninety degrees to the bed, and a rotatable member provided with means adapted to engage the active face of the shoe intermittently and traverse said face and stop and start the bed while in engagement therewith. 30
19. In a printing press, in combination, a frame, an impression member, a bed mounted in said frame and mechanism for reciprocating said bed, said mechanism comprising a rack secured to said bed, a gear adapted to be engaged with and disengaged from said rack, a reversing shoe secured to said bed and having a single active face disposed throughout its length at an angle of less than ninety degrees to the bed, a rotatable member provided with a wrist or crank pin, said pin being adapted to engage with said active face and being rotatable about the same axis as said gear, said pin having a radius of rotation less than the radius of the pitch circle of said gear, whereby a multiplying effect in the movements of the bed is effected between the pin and the active face of the shoe during the reversing operation, 40
- said pin engaging the shoe while said gear is disengaged from the rack. 50
20. In a printing press, in combination, a frame provided with ways, an impression member, a bed mounted in said ways and mechanism for reciprocating said bed, said mechanism comprising a rack on said bed, a pair of reversing shoes secured to the bed, each of said reversing shoes being provided with an active face disposed throughout its length at an angle of less than ninety degrees to the bed, a gear adapted to be engaged with and disengaged from said rack and a pair of rotatable members, each provided with a crank or wrist pin adapted to engage with one of the active faces of said shoes, one of said wrist or crank pins having a radius of rotation less than the radius of the pitch circle of said gear and being rotatable about the same axis as the axis of rotation of said gear. 60
21. In a machine of the character described, in combination: a reciprocating bed; and mechanism for reciprocating said bed including a depending reversing shoe secured to the bed and a rotating member, the latter being provided with means adapted to engage said shoe and stop and start the bed while in contact therewith, said means on the rotating member acting on the shoe at all times while in engagement therewith with forces that can be resolved into horizontal and downward vertical components, whereby the bed is held down firmly on its supports and prevented from rising during the reversing operation, substantially as specified. 70
22. In a machine of the character described, in combination: a reciprocating bed; a mechanism for reciprocating said bed including a depending reversing shoe secured to the bed and a movable member, the latter being provided with means adapted to engage said shoe to stop and start the bed while in contact therewith, said means on said member acting on the shoe at all times while in engagement therewith with forces that can be resolved into horizontal and downward vertical components, whereby the bed is held down firmly on its supports and prevented from rising during the reversing operation, substantially as specified. 80
23. The combination of a reciprocating bed, a reversing shoe secured to the bed and having its active face disposed throughout its length at an angle of less than ninety degrees to the bed, and a movable member adapted to engage said face of the shoe and entirely reverse the bed while in engagement therewith. 90
24. In combination, a frame provided with ways, a bed adapted to reciprocate on said ways; and mechanism for reciprocating said bed, including a reversing shoe secured to the bed having a single active face dis- 100

- 130

posed at an angle of less than ninety degrees to the bed; and a movable member adapted to engage said face of the shoe and reverse the bed.

5 25. In combination, a frame; a reciprocating bed mounted in ways in said frame; and mechanism for reciprocating said bed, including a rotating member, and a reversing shoe secured to the bed and having a single active face disposed at an angle less than a right angle to the bed, and extending both above and below a horizontal plane passing through the axis of rotation of the rotating member; said rotating member being adapted to engage said face of the shoe and reverse the bed.

26. In combination, a reciprocating bed; and mechanism for reciprocating said bed, including a rotating member provided with a crank pin, and a reversing shoe secured to said bed, said shoe having a single active face disposed at an angle of less than ninety degrees to the bed, with which face said pin is adapted to engage to reverse the bed; said active face of the shoe having portions thereof extending both above and below a horizontal plane passing through the axis of rotation of said rotating member; said pin moving about the same axis as said rotating member and having a radius of rotation less than the radius of the circle circumscribed by said member whereby a multiplying effect in the movements of the bed is effected between the pin and the active face during the stopping and starting, substantially as specified.

27. In combination, a frame; a bed thereon; and mechanism for reciprocating said bed, said mechanism including a pair of spaced reversing shoes secured to the bed, each shoe having a single active face disposed throughout its length at an angle of less than ninety degrees to the bed, said

shoes being oppositely arranged; and means adapted to engage said shoes alternately and reverse the bed while in engagement with each shoe.

28. In combination, a frame; a bed; and mechanism for reciprocating said bed, including a pair of spaced reversing shoes secured to the bed, each shoe having a single active face disposed at an angle of less than ninety degrees to the bed, said faces being oppositely arranged, and a pair of movable members each adapted to engage only one of said shoes and entirely reverse the bed while in engagement therewith.

29. In combination, a frame; an impression member mounted thereon; a bed; and mechanism for reciprocating said bed, comprising racks on the under side of the bed, a pair of oppositely rotating gears adapted to mesh alternately with said racks, a depending reversing shoe secured to the bed having a single active face disposed at an angle of less than ninety degrees to the bed, and a movable member adapted to engage said face of the shoe and reverse the bed.

30. In a printing press, the combination of an impression cylinder; a reciprocating bed; and mechanism for reciprocating said bed, including racks and gears meshing therewith, a pair of depending reversing shoes secured to the bed near the ends thereof, each shoe being provided with a single active face disposed at an angle of substantially forty-five degrees to the bed, and a pair of movable members adapted to engage said shoes and reverse the bed, whereby forces acting on the bed during the reversing operation will tend to draw the bed downwardly.
